UNITED STATES PATENT OFFICE.

LEANDER C. JONES, OF BATTLE CREEK, MICHIGAN.

DESIGN FOR A TOY GAS-STOVE

60,032.

Specification for Design.

Patented Dec. 20, 1921.

Application filed June 9, 1920. Serial No. 387,754. Term of patent 3½ years.

To all whom it may concern:

Be it known that I, LEANDER C. JONES, a citizen of the United States, residing at Battle Creek, in the county of Calhoun and State of Michigan, have invented a new, original, and ornamental Design for a Toy Gas-Stove, of which the following is a specification, reference being had to the accompanying drawings, forming a part thereof, in which—

The figure is a perspective front view of my toy gas stove.

I claim:

The ornamental design for a toy gas stove, as shown.

LEANDER C. JONES.
